UNITED STATES PATENT OFFICE.

SAMUEL A. BENNER, OF PITTSBURGH, PENNSYLVANIA.

TRUCK-BOLSTER.

1,230,268.

Specification of Letters Patent. Patented June 19, 1917.

Application filed September 19, 1913, Serial No. 790,656. Renewed November 11, 1916. Serial No. 130,921.

To all whom it may concern:

Be it known that I, SAMUEL A. BENNER, a citizen of the United States, and resident of Pittsburgh, in the county of Allegheny and 5 State of Pennsylvania, have invented a new and useful Improvement in Truck-Bolsters; and I do hereby declare the following to be a full, clear, and exact description thereof.

My invention relates to improvements in 10 car parts and is particularly, though not exclusively, concerned with improvements in the construction of the body of a truck bolster. The object of the invention is the production of a truck bolster having great 15 strength to sustain the excessive weight of heavy cars now in common use, and at the same time to secure lightness of construction so that the weight upon the wheels of the car will not be materially increased, and finally, 20 to produce a bolster possessing the above qualifications which may be manufactured with the greatest economy.

With these objects in view the invention 25 consists in a construction and arrangement of parts the preferred embodiment of which is illustrated in the accompanying drawing in which Figure 1 is a perspective view of a section or blank from which the bolster may be constructed; Fig. 2 is a side-elevation of a 30 bolster body complete; Fig. 3 is a vertical section taken longitudinally of the bolster body; Fig. 4 is an end elevation of the complete bolster; and Fig. 5 is a transverse section on the line 5—5 Fig. 2, and Fig. 6 is a 35 modification.

The first step in the production of my improved bolster consists in the rolling of a section or blank 1, as shown in Fig. 1. This section which may be readily rolled in a 40 manner well known to those familiar with the art of metal rolling, consists of an upwardly opening continuous channel member 2 having side walls or flanges 3, 3, extending up from one side of the web 4 of the section. 45 From the lower side of this web and offset from the outer face of the flanges 3, 3, of the upper channel member are the depending flanges arranged in pairs 5, 5 and 6, 6, respectively, forming downwardly opening 50 channel members of which the web 4 forms the basis. The rolled strip of the character described is then cut into sections of a length suitable for the proposed bolster. This section is then placed in a suitable shearing 55 press by which the downwardly extending

channel members formed by the web 3 and the flanges 5, 5, and 6, 6, respectively, are sheared off from the body of the bolster section between the points 6', 6', Fig. 2, and these channel portions are bent downwardly to 60 form tension members 7. During the shearing and bending down operation the upper or pressure member of the bolster body formed by the upwardly extending channel flanges 3, 3, may be held against bending or 65 distortion in any suitable manner and if desired the ends of the bolster may be clamped so that in the bending down of the tension members 7 the metal of said tension members may be stretched as well as bent. When the 70 bolster body is brought to the proper shape as shown in Fig. 2 by such bending and stretching, the pressure member and the depending tension members may be reinforced and secured together by short struts 8, 8, of 75 I-beam or other suitable construction, rolled, cast or forged and riveted both to the pressure member and the tension members as shown. The body may then be suitably 80 bored and provided with the usual equipment of center plate and side bearing plates as desired. In some instances it may be desirable instead of stretching the tension members 7 as above described, to merely 85 bend the same to shape. In such case the section or blank from which the body is to be formed may be of greater length than the length of the complete body and in the bending operation the extremities of the body 90 will be drawn up together so that the pressure member formed by the channel flanges 3, 3, and the portion of the web 4 between them may be slightly bowed upwardly at the center. In such case, however, the struts 8, 8, when in position will securely hold the 95 pressure and tension members rigidly together and in proper relative position. If desired the ends of the bolster may be reduced by shearing the flanges of the tension members either along the lines A or B, Fig. 100 2, and also the flanges of the pressure members along the line C Fig. 2. In the modified form, Fig. 6, the tension member may have the additional strengthening flanges 9—9 at their outer edges. 105

From the above description, it will be seen that the complete truck bolster comprises a pressure member of continuous channel form throughout the length of the bolster by which great strength in the pressure factor 110

of the bolster is secured, and the tension members 7 are also of continuous channel form, the side walls or flanges of the channels extending downwardly and therefore 5 imparting the greatest possible tensile strength and resistance to tension stress on the bolster. It is obvious that this construction may be employed in other relations, as for example, for a car sill or side frame, but 10 in any event it is peculiarly adapted to resist the strains and stresses both vertical and lateral to which car parts are ordinarily subjected.

While I have herein described and shown 15 a particular embodiment of the invention it is to be understood that the same may be altered in details and in the arrangement of parts within the scope of the appended claims.

20 What I claim is:

1. A truck bolster formed of a rolled section having a pressure member formed of a continuous upwardly opening channel portion and a tension member formed of a continuous downwardly opening channel member, said tension member being sheared from and bent downwardly intermediate the ends of said section.

2. A truck bolster formed of a rolled section having a pressure member consisting of a continuous upwardly opening channel portion and a tension member formed of parallel continuous downwardly opening channel members extending along either side of said 35 pressure member, said tension member being sheared from the rolled section intermediate the ends thereof and bent downwardly to form truss members.

3. A truck bolster formed from a single 40 rolled section comprising a continuous upwardly opening channel member extending centrally of said section and a tension member formed of continuous downwardly opening channel members extending longitudinally along either side of said pressure member, said tension member being sheared from

the body of the section intermediate the ends thereof and upon either side of said pressure member and bent downwardly to form truss members.

4. A truck bolster formed from a rolled section comprising a continuous upwardly opening channel member extending centrally along said section, and continuous downwardly opening channel portions extending longitudinally upon either side of said upwardly disposed channel portion, said downwardly opening channel portions being sheared from the body of the section intermediate the ends thereof and bent 60 downwardly to form tension members.

5. A truck bolster formed of a rolled channel having a pressure member formed of a single continuous upwardly opening channel portion extending centrally from end to end 65 of said section, and a tension member formed of two continuous downwardly opening channel members on either side of said pressure member, said tension members being sheared from and bent downwardly intermediate the ends of said section, and a strengthening member interposed between said pressure and tension members adjacent the center of the bolster body.

6. A truck bolster formed of a rolled section having a pressure member formed of a continuous upwardly opening channel portion, and a tension member formed of continuous downwardly opening channel portions upon either side of said pressure member, said tension members being sheared from and bent downwardly intermediate the ends of said section and parallel strengthening members spaced apart and extending between the central portion of said pressure 80 and tension members.

In testimony whereof, I the said SAMUEL A. BENNER have hereunto set my hand.

SAMUEL A. BENNER.
